DISHWASHING MACHINE

Lawrence A. Loeb, New Haven, Conn.

Application November 25, 1940, Serial No. 367,020

6 Claims. (Cl. 134—58)

This invention relates to dishwashing machines, and more particularly to a household dishwashing machine designed to be placed in the kitchen of a home and used by the ordinary householder. The features of construction are, of course, not confined to this use, but may be employed in dishwashing machines constructed for use in any situation.

The invention particularly relates to a dishwashing machine which is adapted to be supported from the floor. Machines of this character have in the past been of relatively expensive construction, and the expense thereof has been a factor in restricting their distribution. Moreover, in some instances machines of this character now upon the market are provided with controlling devices for controlling the various operations of the machines, which controlling devices are not as convenient as might be desired.

One object of the invention is the construction of a dishwashing machine which is efficient in operation and economical to manufacture so that it may be sold at a relatively low price.

A further object of the invention is the provision of an improved controlling mechanism to control the performance of the various operations of the device by manipulation of a single control member.

To these and other ends the invention consists in the novel features and combinations of parts to be hereinafter described and claimed.

In the accompanying drawings:

Fig. 1 is a perspective view of a dishwashing device embodying my invention;

Fig. 2 is a partial sectional view on line 2—2 of Fig. 1;

Fig. 3 is a sectional view taken at right angles to the section shown in Fig. 2;

Fig. 4 is a rear elevational view of the portion of the front case showing the control mechanism;

Fig. 5 is a side elevational view of the parts shown in Fig. 4;

Figs. 6, 7 and 8 are views similar to Fig. 4, but showing the control disk in various positions; and

Fig. 9 is a detail elevational view of the control disk.

To illustrate a preferred embodiment of my invention I have shown a dishwashing machine which comprises an outer case 10 and an inner tub or vat 11 supported from the floor upon legs 12. The bottom of the tub is shown at 13, from which portion the bottom slopes upwardly upon all four sides, as shown at 14, to meet the side portions of the tub. Mounted below the tub is a

motor 15 having a shaft 16 to actuate an agitating means for the water in the tub. As shown this means is in the form of a propeller 17 having blades 18 and 19 of a form similar to that of a motor boat propeller, for example. The propeller is mounted on the motor shaft, which extends through the bottom of the tub.

It will be noted that at its upper portion the tub 11 is provided with an opening 20, this opening being defined by stepped portions or flanges 21 and 22, and that the case 10 is provided with a flange 23 which enters the opening 20 and fits snugly against the flange 21.

A cover 24 is provided for the opening 20, the cover being hinged at 25 and being provided with stepped flanges to lie against the flanges 21 and 22, and also a depending flange 26 projecting downwardly from the flange 22 so as to effectually seal the opening against leakage of water when the latter is agitated during the dishwashing operations.

It will be noted that the tub 11 is provided along two sides with inclined upper portions 27, and extending from these members to the flanges 21 are baffles 28, which baffles are adapted to cooperate with the inclined sides 27 to deflect the water upon the rear surfaces of the dishes in the racks, and particularly the upper rack, as will be hereinafter described. Similarly baffles may be provided at the front and back of the tub, as shown at 28^a. The cover 24 may be provided with a transparent or glass portion 29, so that the operation of the machine may be viewed while the cover is closed.

Within the tub are provided upper and lower dish racks to hold the dishes in place, the upper dish racks being designated by the numeral 40 and the lower dish rack by the numeral 50. As no claim is made to the specific structure of these dish racks in the present application, a detailed description thereof is unnecessary.

Adjacent the rear wall of the tub is a tube 56 communicating at its lower end with a bent tube 57 leading into the tub, and in this tube 45 is mounted a float 58 having a stem 59 secured at its upper end to an indicator 60 by which the level of the water in the tub may be readily indicated to the operator.

A drain pipe 61 communicates with the lower 50 portion of the tub, the communication being controlled by a valve 62, the stem 63 of which is connected to one end of a lever 64 pivoted at 65, and normally urged by a spring 66 into a position to hold the valve in raised or open position. 55 Also communicating with the lower portion of the

tub is an inlet pipe 67 passing upwardly to a valve housing 68 within which is an ordinary spring-pressed control valve 69 secured to the stem 70, so that when the stem is pressed inwardly or upwardly, as shown in Figs. 3 and 5, the valve will be opened to admit water from a source of supply to the tub. An overflow pipe 61^a communicates with the tub at its upper end and with the drain pipe at its lower end.

The inlet and outlet of the tub, as well as the operation of the motor 15, is controlled by a single control disk 75, shown in Figs. 4 to 9, which disk is secured to a rotatable stem 76 projecting through the outer casing 10 and having secured at its outer end a control handle or operating member 77. With reference to Fig. 3, it will be seen that at the front the outer housing 10 is spaced some distance from the front wall of the tub, so that the inlet pipe 67, the valve casing 68, and the control apparatus may all be mounted between the tub and the outer casing and supported upon a member 78 secured to the tub.

The disk 75, which is rotated by the handle 77, is provided with an eccentric pin 79, to which is secured a link 80 connected at its lower end to a spring 81, the spring being in turn connected to a rod 82, the lower end of which has a one-way connection at 83 with the control arm 64 of the outlet valve 62. It will be apparent that when the disk 75 is in the positions shown in Figs. 6 and 7, wherein the pin 79 is within the upper range of its movement, the controlling member 64 will be raised and the valve 62 will be closed, and conversely, when the disk is in the positions shown in Figs. 4 and 8 and the pin 79 at the lower range of its movement, the spring 66 will draw the arm 64 downwardly and raise the valve 62 to drain the tub.

In order that the supply of water to the tub will be controlled by the disk 75, the latter is made of elliptical shape, being greater across one diameter than another. The edge of the disk contacts the upper edge of a lever 85, which engages the lower end of the valve stem 70, whereby, when the disk 75 is in the positions shown in Figs. 6 and 8, wherein the longer diameter is vertically disposed, the lever 85 will be moved downwardly to open the valve and admit water to the tub. When, however, the disk is in the positions shown in Figs. 4 and 7, with the shorter diameter vertically disposed, the valve 68 will be closed by its spring. The edge of the disk 75 may be provided with notches 86 to merely locate this disk in each of its four positions by engaging the upper edge of the lever 85, so that there will be more or less of a positive stopping place or station for this disk at each of the four points in its revolution. It will be understood that these notches 86 have nothing to do; however, with operating the lever 85 and opening the valve 69.

As stated, the disk 75 also serves to control the motor 15, and for this purpose the front face of the disk is provided with an arcuate contact member 89 of substantially quadrantal form, this member being adapted to engage vertically spaced contacts 90 and 91 serving to close the circuit to the motor in any desired way. When the contacts 90 and 91 are both engaged by the member 89 of conducting material, the circuit will be closed. When, however, the contacts are not in engagement with this member, the circuit will be open, and the motor will be out of operation. If the contacts 90 and 91 are formed of carbon, this material may be rubbed off upon the face

of the disk and short-circuit the two contacts even when they are not in engagement with the conducting member 89. For this purpose the face of the disk upon which the member 89 is mounted may be provided with radially disposed slots or recesses 92, which will break the rings of carbon which otherwise might form upon the disk and prevent the short-circuiting of the contact members 90 and 91.

10 The operation of the controls may be best explained by reference to Figs. 4 to 9. With the handle 77 in the position shown in Fig. 3, the parts are in the position shown in Fig. 4, wherein the drain is open, the water inlet valve 69 is closed, and the motor is at rest. This will be the position of the parts when the machine is out of operation.

When it is desired to use the machine, the handle 77 is given a turn in the direction to move the disk 75 according to the arrows in Figs. 4, 6, 7 and 8. The disk is first moved through an angle of 90° to the position shown in Fig. 6. In this position the pin 79 will be at the upper portion of its orbit, and the drain will, therefore, be closed.

20 Also the larger diameter of the disk will be in a vertical direction, and therefore the lever 85 will be moved downwardly to open the valve 69 and permit the filling of the tub. The motor, however, will not be in operation. When the gauge 60 shows that the desired quantity of water is in the tub, the handle 77 is given a further turn through an angle of 90° to the position shown in Fig. 7. As the pin 79 is still at the upper portion of its movement, the drain valve will still be closed,

25 but the shorter diameter of the disk will be disposed vertically and the inlet valve 69 will be closed. It will be noted that the contacts 90 and 91 will, as shown in Fig. 7, be engaged by the contact member 89 on the disk, and at this time 30 the motor will be placed in operation. The machine will now be performing the washing operation, in that the tub will be filled with water, both drain and inlet valves will be closed, and the motor will be rotating the agitator 17. When the dishes have been cleaned, the control member 77 will be turned through a further angle of 90° to the position shown in Fig. 8. In this position the motor will still be in operation, as the contacts 90 and 91 will still be engaged with the contact member 89, but the drain valve will be open, and likewise the inlet valve 69 will be open, thus permitting the used water to drain from the tub while at the same time admitting fresh water and also operating the agitator. This is the rinse position of the parts, the fresh water which enters through the inlet valve 69 being thrown up over the cleansed dishes to rinse them. After the dishes have been thoroughly rinsed, the control member 77 is again turned through an angle of 90° to the normal inoperative position of the parts shown in Fig. 4.

35 While I have shown and described a preferred embodiment of my invention, it will be understood that it is not to be limited to all the details shown, but is capable of modification and variation within the spirit of the invention and within the scope of the appended claims.

What I claim is:

40 1. In a dishwashing machine, a tub having an inlet and a drain, valve means for controlling said inlet and drain respectively, a disk-shaped rotatable controlling element having a cam portion thereon, extensible means connected to said element and to said drain valve to actuate the latter, an inlet valve actuating member, said

member being engaged by the cam portion of said element for actuation thereby, an agitator in the tub, an electric motor to drive said agitator having a switch, and a contact closing element on said disk-shaped element to close the motor switch in certain positions of said element.

2. A dishwashing machine comprising a case, a tub therein having an inlet and a drain, a valve member controlling the inlet, a second valve member controlling the drain, the first valve member being spring pressed to closed position and the second being spring pressed to open position, an agitator in the tub, a motor to rotate the agitator, a switch to control said motor, controlling means mounted between said tub and case comprising a horizontally disposed rotatable shaft extending to the exterior of the case for manual manipulation, a disk on said shaft, means mechanically connecting said disk with said valves to move the latter against the action of said springs, the connection to said drain valve comprising a tension-exerting extensible member to permit movement of said disk while said valve remains closed and means on said disk to actuate the motor switch.

3. A dishwashing machine comprising a tub having an inlet and a drain, valve means for controlling said inlet and drain respectively, a disk-shaped rotatable element, an actuator for the inlet valve extended to a point adjacent said element, said element having an eccentric portion thereon to operate said actuator, and an extensible tension-exerting member connected to said element and to said drain valve to operate the latter, said means being eccentrically connected to said element.

4. A dishwashing machine comprising a tub having an inlet and a drain, valve means for controlling said inlet and drain respectively, a disk-

shaped rotatable element, an actuator for the inlet valve extended to a point adjacent said element, said element having an eccentric portion thereon to operate said actuator, and connecting means connecting said element to said drain valve to operate the latter, said means being eccentrically connected to said element and including an extensible tension-exerting member to draw the drain valve to closed position and to permit movement of said element while said drain valve remains closed.

5. A dishwashing machine comprising a tub having an inlet and a drain, valve means for controlling said inlet and drain respectively, a disk-shaped rotatable element, an actuator for the inlet valve extending to a point adjacent said element, said element having oppositely disposed eccentric portions thereon to operate said actuator, and an extensible tension-exerting member connecting said element to said drain valve to operate the latter, said member being eccentrically connected to said element.

6. A dishwashing machine comprising a tub having inlet means and drain means, a valve for controlling each of said inlet and drain means, said drain means comprising a valve seat against which the drain valve rests to close the drain, a disk-shaped rotatable element, means connecting said element to the inlet valve to actuate the latter, means connecting said element to the drain valve to draw the latter against its seat and close the drain, said last-named means being eccentrically connected to said element and including a tension member which is yieldingly extensible whereby limited movement of said element is permitted without movement of said drain valve.

LAWRENCE A. LOEB.
